UNITED STATES PATENT OFFICE

2,355,796

PRINTING MACHINE

Walter T. Gollwitzer, Euclid, Ohio, assignor to
 Addressograph-Multigraph Corporation, Wil-
 mington, Del., a corporation of Delaware

Application February 26, 1940, Serial No. 320,778

22 Claims. (Cl. 101—57)

This invention relates to printing machines and mechanisms for use therein and therewith such as computing, accumulating, paging and proofing, number and numerical accounting data, printing, sub-totaling, and kindred mechanisms, and the primary object is to expedite preparation of business instruments and the like and records thereof and in this connection it is to be understood that the term "business instruments" is used hereinafter in the generic sense with reference to a wide variety of sheets of which specific examples are checks drawn on banks, public utility bills, insurance notices, invoices and the like.

This application is a continuation in part of my application Serial No. 221,841, filed July 28, 1938, now issued as United States Letters Patent No. 2,296,277, patented September 22, 1942.

Exemplifications of printing machines of the kind to which this invention generally pertains are to be found in, for example, United States Letters Patent 2,041,183, 2,083,061, 2,132,411 and 2,132,413. Usually a roll of paper is mounted in proper relation with machines of this kind and a web is withdrawn therefrom and led to the machine. Sheets cut from this web, or which are removed from a stack of pre-cut sheets stored in the machine, are fed through the machine past one or more printing positions whereat impressions are made thereon either directly from printing, printing and control, or like devices that are sequentially fed through the machine or from suitable printing mechanisms set up under control of printing and control or like devices or record cards or the like. Furthermore, in machines of this kind constantly reoccurring data are printed on the sheets before pre-cut sheets are stacked in the machine or before the sheets are severed from a web or after such severance and sometimes such impressions are made on the sheets both prior to and after severance thereof from a web.

The data printed on sheets or business instruments such as those to which reference has been made, other than the constantly reoccurring data, may be conveniently classified as changeable data and variable data. The changeable data are usually those which are directly printed from printing, printing and control, or like devices and usually consist of an identification, such as a name and address, and the variable data are usually numerical accounting data, such as the amount of money to be paid pursuant to a check drawn on a bank

or the amount of money due and owing a public utility, an insurance company or the like and also, sometimes, related data.

Various ways have been proposed heretofore for printing both such changeable and variable data on business instruments and among these has been the use of printing devices, from which the changeable data were printed directly, and record cards, usually perforated record cards, under control of which the variable data were printed. In such usages, an example of which will be found in United States Letters Patent 2,083,061, the printing devices and the record cards are sequentially fed through a suitable printing machine wherein the changeable data are printed by making one or more impressions from each printing device on each business instrument and the variable data are printed by making one or more other impressions on each instrument under control of each record card. It is of course essential that the changeable data printed on each instrument from the printing device be related to the data printed under control of the record card, and vice versa, and to this end the printing devices and record cards have been manually compared before being passed through the machine so as to insure that the devices and cards were arranged in corresponding sequences to thereby insure that the changeable and variable data appearing on each instrument relate to the same person or account or the like.

As a further means of assuring that the changeable and variable data printed on each instrument in such usages will be related to each other, that is, will relate to the same person, account or the like, it has been proposed to equip the machines through which such devices and cards are fed with means for comparing each device and card, from which and under control of which impressions are to be made on a particular business instrument, with each other, and this means is usually operated to interrupt operation of the machine or to afford other indication when a particular printing device and a particular record card relating to a particular business instrument did not correspond. Inasmuch as, in such usages, the sequencing of the printing devices and the record cards was performed manually, the human factor entered into the operations which, of course, gave rise to error, and where the means in the machine operated to interrupt operation of the machine when a particular card and device did not correspond the productive ca-

pacity of the machine was impaired for, obviously, time was lost each time machine operation was interrupted. Furthermore, it is a time consuming task to determine the reason for machine stoppage in such instances and to locate the related printing device and record card which further operated to reduce the productive capacity of the machine.

In view of the foregoing it has also been proposed to provide printing and control devices, an example of which is disclosed in Patent No. 2,132,412. Such printing and control devices include, for example, embossed type characters from which impressions can be made directly and also include a perforated or other area affording control means under control of which the variable data can be printed. The use of such devices eliminates the necessity of comparing printing devices and record cards or the like in order to insure that related changeable and variable data will be printed on the same instrument. However, in those instances heretofore where it has been proposed to employ printing and control devices for producing changeable and variable data on business instruments, the control means provided on the devices were direct representations of the variable data that were to be printed under control thereof. In view of this it was necessary to change the control areas of the printing and control devices each time there was a variation in the variable data. This was required not because of any limitation in the printing and control devices but rather by reason of limitations in the machines in which the printing and control devices were employed, which is to say, such machines heretofore have not been equipped to interpolate the data represented in the control areas of the printing and control devices or, more specifically, such machines have not been equipped to perform computing operations based upon the data represented in the control areas of the printing and control devices.

In view of the foregoing, it has further been proposed to enable data represented in the control areas of printing and control or like devices to be interpolated in the machine through which such devices are passed and more specifically to enable computing operations to be effected in a machine under control of the control areas on printing and control or like devices passed through the machine as more fully disclosed in my co-pending application Serial No. 221,841, now issued as United States Letters Patent No. 2,296,277, patented September 22, 1942.

A specific example of the use of printing and control devices in the preparation of business instruments is the preparation of so-called dividend checks of a corporation by means of which dividends declared by the corporation are distributed to its shareholders. Heretofore where printing and control devices have been employed in the preparation of dividend checks, each printing and control device related to a particular shareholder whose name and address (changeable data) was directly printed from type characters or the like on a printing and control device relating to the particular shareholder and the control area of such device was arranged to bear representations of the amount of dividend to be paid to the particular shareholder. Now it will be recognized that in a long list of shareholders the changes in holdings of the individual shareholders between payments of successive dividends will not be likely to entail nearly as many

variations in the records of the corporation as will occur when the dividend rate of the corporation varies, for when the dividend rate varies it is necessary to change each and every printing and control device if the amount of dividend payable to the respective shareholders is directly represented in the control areas of the devices pertaining to such respective shareholders. It will be apparent from this that a marked advantage will accrue from representing the holdings of a shareholder in a corporation on the printing and control device pertaining to the shareholder rather than directly representing thereon the amount of dividend payable to the shareholder as has been done heretofore.

It is to be understood, when reference is made herein to the preparation of dividend checks of a corporation, that this is merely an exemplary utilization of my invention but one which is common and convenient in describing the various aspects of my invention. However, my invention, as stated heretofore, is capable of use in a wide variety of instances in which sheets are to be printed and among other instances may be cited the preparation of tax bills, public utility bills, insurance premium notices, chain store billings and allied and kindred operations. Therefore, while reference is made hereinafter to the preparation of dividend checks of a corporation, it is to be understood that this is merely exemplary and is not, therefore, to be taken as a limitation of my invention.

Perhaps the most frequent interpolation of data such as may be represented in the control areas of printing and control or like devices is a computing operation entailing multiplication, one factor of each such multiplications for example, being represented in the control area of a printing and control or like device, and the other factor may also be derived therefrom or elsewhere as more fully disclosed in my aforesaid co-pending application Serial No. 221,841. In the preparation of dividend checks of a corporation the factor represented in the control area of a printing and control device to be utilized in such preparation will be the number of shares of stock owned by the shareholder to whom the particular printing and control device relates, and the other factor, the dividend rate, may be included or set up in the machine. In an instance where the dividend rate will remain constant for a large number of operations, multiplications, in such an instance, this factor of the various multiplications may advantageously be, in effect, constantly represented in the machine. The means and method of effecting the multiplications in the present machine, which are of the aforesaid nature, are more fully discussed and disclosed in my aforesaid co-pending application Serial No. 221,841, to which reference is made hereinabove.

In machines wherein business instruments and the like are prepared it is often advantageous to prepare what is known as a proof sheet and in other instances it is desirable to not only produce proof sheets but to also accumulate totals and the like and sometimes only totals are accumulated. Various arrangements have been proposed heretofore for enabling this to be accomplished and usually in such prior arrangements it has been customary to directly set up whatever means are to be operated for accomplishing the foregoing directly from set-up mechanisms in the machine. This, however, sometimes entailed complicated interconnections and

to an appreciable extent limited the flexibility of the machine and the manner in which such operations could be performed and particularly the positions whereat such operations could be performed.

In view of the foregoing, an important object of this invention is to enable the preparation of proof sheets, the accumulation of totals, the production of ancillary or related impressions on sheets, and many of the so-called auxiliary operations to be performed at wide variations of positions in the machine without the necessity of providing physical connection between the mechanisms performing such auxiliary operations and the means by which the mechanisms are set up or controlled.

It is contemplated by my invention that the means which are operated under control of the control areas on printing and control or like devices which, in the present instance, is the multiplying means, will be equipped to not only in some instances accumulate totals and in most instances to display the results of the operations thereof as either by setting up a register or as is done in the present instance by the setting up of type characters, but that an additional record will be produced as by perforating or otherwise providing control means in cards or the like and so to do constitutes another important object of the present invention.

Other objects related to the foregoing are to produce a perforated record card or the like in the course of operation of the machine and to incorporate into such perforated record card perforations or the like representative of the result of an operation of the machine such as, for example, the value of a final product ascertained in the multiplying means; to feed such perforated record cards or the like through the machine in such a way as to enable such cards to be utilized in the performance of operations on the sheet or the like receiving impressions or having other operations performed thereon from the means in which the perforated record cards or the like are produced; to utilize such perforated record cards or the like to set up means for perforating what may well be called auxiliary operations in the machine; to enable one or more of such means for performing auxiliary operations to be located at desired or advantageous positions in the machine and to feed the perforated record cards or the like to such positions whereby physical connection of such means for performing auxiliary operations with the means under control of which such operations are to be performed may be avoided; to employ an accumulator in the machine in which totals or the like may be entered or accumulated under control of perforated record cards or the like produced as an ancillary operation to some other operation in the machine; to employ printing means settable under control of such perforated record cards or the like to produce printed records either on sheets passing through the machine and receiving other impressions or having other operations performed thereon or onto special sheets or webs passed through the machine for the purpose of producing proof sheets and the like; and to enable perforated record cards or the like produced ancillary to some other operation in the machine to be collected for use in controlling other operations in the same or a related machine.

In those instances where what has been called a proof sheet has been prepared, it has usually

been customary to produce the impressions on a web and in some instances this web, after the impressions were made thereon, has been wound into a roll but in other instances predetermined lengths of such a printed web have been fed past a severing means operable to divide the web into sheets or pages of substantially uniform size which were then collected and used as required or desired as, for example, by being bound in loose-leaf binders for checking and reference purposes and the like. Arrangements of this kind are commonly known in the art to which this invention pertains as pagers and proofers, and still another important object of this invention is to provide a novel pager and proofer and particularly one especially adapted for use with the machine of the present invention.

Other objects related to the foregoing are to support a roll from which a web may be withdrawn for passage through the novel pager and proofer of this invention in such a way that the normal operation of the machine with which the pager and proofer is used is not impaired; to avoid the necessity of changing the construction of the machine particularly in so far as the platen or other impression making means are concerned in order to accommodate webs of different widths and enable impressions to be made on the web; to feed the web through a platen or other movable impression making member to enable the web to move therewith without relieving the tension on the web or tearing or otherwise impairing the web; to separate operative portions of the platen or other impression member to afford a slot through which a paper web or the like may be fed; to provide a simple and inexpensive web feeding arrangement adaptable for use as a pager and proofer and a novel severing arrangement for dividing the web at intervals into sheets of a predetermined size and on the whole to provide a simple and economical pager and proofer of efficient and positive operation.

A further important object of this invention is to take what is referred to in the art as sub-totals whenever desired by the operator or automatically at the foot of each proof sheet which sub-totals are the totals of all amounts printed on the proof sheets prior to the taking of the previous sub-total.

Many other objects and advantages of the present invention will be apparent from the following description in which reference is made to the accompanying drawings wherein

Fig. 1 is a perspective view of the machine embodying my invention;

Fig. 2 is an elevation of a typical printing and control device which may be utilized in the present machine;

Fig. 22 is a wiring diagram of the machine insofar as it relates to the present invention.

For a detailed description of that part of the illustrated machine which is not specifically described in this application reference may be made to my aforesaid co-pending application Serial No. 221,841. It may be observed however that in the printing machine shown in Figs. 1 and 5 is so arranged that a roll of paper R may be suitably supported at one end of the machine, and a web W is withdrawn from the roll R and passed into a signature printing and web severing unit 89. The free end of the web W is led past severing means in the unit 89 which is operative at certain times in the course of operation of the machine to sever sheets as S, Fig. 3, from the web W. The sheets thus severed from the web W are deposited in a sheet guideway G provided longitudinally along the table top of the machine. The sheets S are fed along the guideway G so as to come to rest in a first printing position associated with the multiplying mechanism M and at this position variable numerical data or amounts are printed on the sheet. Such numerical amounts are determined by the multiplying mechanism M under control of means embodied in printing and control devices D, Fig. 2, which are passed through the machine, the details of the structure and function involved in this operation being described in detail in the aforesaid parent application Serial No. 221,841. The sheet is then advanced to a second printing position beneath an impression means such as a platen P, and the platen is operated to produce an impression on the sheet S from printing means embodied in the same printing device from which the variable numerical data printed on the sheet was derived. The printing devices D are withdrawn one by one from the bottom of a magazine H mounted on the rear ends of a pair of guide rails 254, and the printing devices are advanced forwardly in a step by step manner along a guideway formed in part by the rails 254. In such advancing movements the printing devices D come to rest on an anvil 264 so that impressions may be made therefrom by the platen P. The advancing movements are imparted to the printing devices D by single cycle advancing means 300 controlled from a main coordinated control means such as the

main control cam shaft of the machine by means including a control cam shaft of the machine by means including a control solenoid 310, as described in detail in the parent application Serial No. 221,841. After the desired impression or impressions have been made from a printing device D, the advancing means discharges the printing device forwardly and it is deposited in a collecting means such as one of the drawers J.

10 After an impression has been made by the platen P on a sheet S from a printing device D, the sheet S is further advanced along the sheet guideway G and is passed through a form printing unit U so that reoccurring lines or text matter may be printed thereon. The completed checks or sheets S are discharged from the form printing unit U into a suitable sheet collector K.

In instances where, for example, as in the present instance, checks are being printed and in many other operations, it is desirable to preserve a record of what has been printed on sheets as S and to this end what is known as a proof sheet is prepared. Such proof sheet is usually prepared in the form of a web and this web is subsequently divided at predetermined intervals to afford sheets or pages of uniform size that may be conveniently bound as in loose leaf binders or the like to thereby afford a permanent record of what is printed in the course of a run of the machine. Mechanisms which so print on webs and which divide the webs into pages affording proof sheets have come to be known as pagers and proofers and such mechanism is embodied in the machine disclosed herein.

35 The pager and proofer in the present instance is generally indicated by 900 and operates to produce a proof sheet such as is fragmentally illustrated in Fig. 4 and which is indicated by 901, this proof sheet passing through the machine in the form of a web 901—W. The proof sheets 901 desirably include data A' printed from the printing means of the printing devices D, as well as a number N' and numerical data V' all of which are arranged in lines across the proof sheet or web in such a manner that the data A', N' and V' in each line constitute duplicates of data printed on a particular check or sheet S.

40 In the machine as herein shown the data A', N' and V' are printed on the proof sheet or web 901—W at the same printing station at which the data A are printed upon the checks or sheets S, the proof printing operations being accomplished in alternate machine cycles during which a sheet S is not present beneath the platen P. In the accomplishment of this proof printing operation the machine herein shown utilizes an auxiliary printing mechanism VP, Fig. 5, disposed in operative relation beneath the platen P and arranged to be variably set up under the control of the multiplier M to print numerical amounts corresponding with amounts previously printed by the multiplier. Thus, as explained in detail in the parent application, the machine has punching mechanism PM operatively associated with the multiplying mechanism M so as to produce individual punched cards having perforations therein corresponding with the numerical amounts ascertained and printed by the multiplier. These cards are advanced along a card guideway CG, to a sensing station associated with the auxiliary printing mechanism VP where the numerical amounts represented on the cards are sensed and set up in the auxiliary printing mechanism VP. Thus when the platen is operated to print the data A' on the proof sheet or web, the

platens will act as a back up member to enable hammer mechanism in the auxiliary printer VP to print the set up numerical amount on the proof sheet in the appropriate line thereof.

In the present instance the web 901—W, Fig. 5, is withdrawn from a roll 901—R which is rotatably mounted in a stand 902. This stand comprises spaced upright brackets which have bifurcations as 903 in the upper edges thereof and pairs of rollers as 904 are mounted on the stand adjacent the bottoms of these bifurcations so that a shaft 905 on which the roll 901—R is supported may rest on these rollers to thereby afford a frictionless support for the roll, and in this way inertia incident to the withdrawal of the web 901—W from the roll is substantially reduced.

In the present instance the web 901—W is withdrawn from the roll 901—R and passed about a roller 906 in the stand 902 and from this roller the web is led across the bottom of the machine 20 to a roller 907 carried by brackets as 908 which are secured to uprights as 258 of the frame. From the roller 907 the web passes to a roller 909 mounted between side plates 910 and 911, Fig. 14, which depend from the side plates 912 25 and 913 of the pager and proofer unit, the roller 909 being part of a web looper.

A roller 911 is the movable part of the looper for the web 901—W and to this end vertical slots as 914 and 915, Figs. 5 and 10, are provided in the side plates 910 and 911 and the ends of a shaft 916 are disposed in these slots, the roller 917 being carried by the shaft 916. Another shaft 918 is journaled in the side plates 910 and 911 and carries a roller 919 that is also part of the looper for the web 910—W. The roller 909 has friction means such as rubber bands provided on the periphery thereof to insure good frictional engagement thereof with the web 901—W. As shown best in Figs. 8, 12 and 14, a worm wheel 920 is fast on the shaft carrying the roller 909 and a worm gear 921 on the shaft of a motor 922 meshes therewith, this motor being set in operation when the loop, drawn in the web 901—W by the roller 917 between the rollers 909 and 919, is reduced in size.

Hence, means responsive to the size of this loop are provided and to this end one end of the shaft 916 is engageable with a cam surface on an arm 923 which is pivotally mounted as indicated at 924 on the side plate 911. The arm 923 carries a pin 925 of insulating material that is engageable with a switch blade 926 that carries a contact which is engageable with the contact on the switch blade 927. As the web passes over the roller 919 in such a way as to reduce the size of the loop drawn in the web by the roller 917, the shaft 916 moves up into a position substantially like that shown in Fig. 13, whereupon this shaft acts on the cam surface on the arm 923 and through the pin 925 this engages the contacts on the blades 926 and 927 to thereby close the circuit to the motor 922 which thereupon rotates the shaft carrying the roller 909 to withdraw the web 901—W from the roll 901—R. Thereupon the loop in the web increases in size and as the size of the loop between the rollers 909 and 919 is increased to the size desired the roller 917 moves downwardly and the shaft 916 so moves along the cam surface on the arm 923 that the contact on the blade 926 is separated from the contact 927 to open the circuit to the motor 922 whereupon further withdrawal of the web from the roll 901—R is interrupted when the loop attains the desired size.

As the web 901—W passes from the roller 919 it is led over the impression face of the platen P, the web being of such a width and so extending across the impression face 635 that impressions 5 may be made thereon from a printing and control device D disposed on the anvil 264, the type characters on the wheels of the numbering device and on the type segments of the auxiliary printing mechanism VP, respectively. From the impression face of the platen P the web 901—W passes to a pair of rollers 930 and 931 mounted between rearwardly projecting extensions on the plate 649 so that the web passes up over what may be called the rear face of the platen P, and from the roller 931 the web 901—W is passed between the plates 639 and 586 of the platen P.

From the space between the plates 639 and 586 the web passes to a roller 932 rotatable on a shaft 933, the ends of which are mounted in arms 934 and 935, Figs. 8 and 10, which depend from the bearings 936 and 937 on the side plates 912 and 913 and in which bearings the shaft 938 is journaled. The ends of the shaft 933 extend through arcuate slots as 939 in the side plates 912 and 913 and by means of bolts as 940 passed into the ends of the shaft as 933, the roller 932 may be maintained in adjusted positions. The adjustment afforded for the roller 932 enables adjustment in a loop defined in the web intermediate 30 the roller 931 and a roller 941 on the shaft 938. An adjustment of the size of this loop varies the location of matter printed on the web 901—W and the position at which severing means, described hereinafter, is operative to divide the web 35 into pages so as to thereby regulate the size of the pages and insure severing of the pages intermediate impressions made thereon rather than through such impressions.

The side plates 912 and 913 are tied together 40 by cross members as 942 so that a unitary construction is provided to enable the pager and proofer to be handled as a unit. Inasmuch as the web 901—W may vary in width in different runs, the side plates 910 and 911, which have been described as depending from the side plates 912 and 913, are adjustably mounted on a cross bar 943 by the use of clamping screws as 944, this arrangement enabling the plates 910 and 911 to be spaced from each other sufficiently to neatly 45 accommodate different widths of web therebetween. It will also be understood that the rollers 909, 917 and 919 may be discontinuous to additionally furnish accommodations for webs of different widths.

The amount of travel of the platen is relatively 50 restricted and the passes of the web 901—W to and from the platen are in substantially straight lines and hence in the reciprocatory movement of the platen P described hereinabove the length of 55 these passes of the web is not changed to such a degree that the web becomes slack, this also being augmented by the tension applied on the web by the roller 917, it being understood that the shaft 916 is at no time enabled to seat in the bottom of slots as 915 in the course of operation of the motor 922 to increase the size of the loop in the web.

Inasmuch as impressions are made on the web 70 901—W at spaced intervals and as, in the present instance, such impressions are made in alternate impression operations of the platen P and since the impressions made on the web 901—W are to be spaced one from the other in predetermined amounts, a step by step advancing movement is

imparted to the web 901—W and in the present instance such movement is imparted to the web as it passes about the roller 941. As can be seen in Figs. 7 and 10, a clamping roller 945 is fast on a shaft 946 which is journaled in bearing blocks 947 and 948 which, as shown best in Fig. 7, have slots as 949 in opposite edges thereof, the portions of the bearing blocks intermediate these slots being fitted into bifurcations as 950 in the upper edges of the side plates 912 and 913 to thereby afford a slidable mounting for the bearing blocks 947 and 948, the shaft 946 and the clamping roller 945. In order to maintain the clamping roller 945 in web clamping cooperation with the roller 941, cross bars or strips as 951 are secured to the bearing blocks as 948, Figs. 10 and 16, and springs as 952 extend between these strips and spring anchors on the adjacent side plate, these springs being effective to urge the periphery of the clamping roller 945 into web clamping cooperation with the roller 941. A web advancing step by step movement is imparted to the shaft 938 and the roller 941 in a manner described hereinafter.

The web 901—W passes from the roller 932 and about the roller 941 through the bite between this roller and the clamping roller 945 and thence over a ledge 953, Fig. 10, that is fast to a cross bar 954 which extends between the side plates 912 and 913. A stationary cutting member 955 is fast on the upper edge of the cross bar 954 and a movable knife 956 is adapted for cooperation therewith, this movable knife 956 being a thin strip of metal and being fast to the concave face of the carrier bar 957, the cutting edge of the movable knife 956 being tapered inwardly and upwardly from the ends thereof, and this in cooperation with the longitudinal arc imparted to the knife 956 by connection thereof to the above described concave face insures a shearing action in the course of cooperation of the knife 956 with the cutting edge of the stationary cutting member 955 during downward movement of the knife that is effected in the manner now to be described.

The carrier bar 957 is acted on by a spring 957' to hold the knife 956 in engagement with the member 955 and this bar extends between and is carried by arms 958 and 959, Figs. 7 and 10 which, at their lower ends, are pivotally connected to arms 960 and 961 that are pivotally mounted on studs 962 fixed in the side plates 912 and 913, the pivotal interconnection between arms as 958 and 961 being shown at 963, Fig. 10. The arms 960 and 961 are in the form of bell cranks having depending arms 964 and 964' which are rigidly joined together for rocking movement in unison by a cross arm 964a. The arm 964 has a roller 965 at the free end thereof and this roller is urged into engagement with the periphery of a cam 966 by springs as 967 that extend between the arms 960 and 961 and spring anchors on the adjacent side plates 912 and 913. Lugs as 960' extend inwardly from the side plates 912 and 913 and have adjusting screws 961' mounted therein, the lower ends of these adjusting screws engaging the arms 960 and 961 and limiting the upward movement thereof induced by the springs as 967.

The cam 966 is rotatably mounted on the shaft 968 that is journaled in the side plates 912 and 913 and includes a hub 974, Fig. 7. Clutch teeth 969 are provided at the free end of this hub and are adapted for cooperation with clutch teeth 970 provided on the adjacent end of a collar 971 that is fast on the shaft 968. These clutch teeth

969 and 970 and the parts controlling engagement thereof are substantially similar to those described in my co-pending application Serial No. 239,561, filed November 8, 1938, now Patent No. 2,265,133, patented December 9, 1941.

A plate 972, Fig. 7, rotatably mounted on the shaft 968 is suitably connected, as by pins, to the cam 966. Springs as 973 extend between this plate and the cam 966 whereby the plate is urged into engagement with the inner face of the side plate 912 and the cam is urged along the shaft 968 to tend to engage the clutch teeth 969 on the hub 974 thereof with the clutch teeth 970 on the collar 971. However, engagement of a pin 975 on the hub 974 with a cam surface 976 on the arm 977 normally holds the clutch disengaged. The arm 977 is pivotally mounted, as indicated at 978, on the side plate 912, a spring 979 being active on this arm to maintain the marginal portion adjacent the free end thereof in engagement with the periphery of the hub 974.

A plate 980 is pivotally mounted at 981 on one arm of a bell crank 982 that is pivotally mounted on a stud 983 carried by the side plate 912. The plate 980 includes a lug 984 that is engageable with the under side of the free end of the arm 977, said plate 980 being urged toward the periphery of the hub 974 by a spring 985. The arm 986 of the bell crank of which the arm 982 is a part is loosely and pivotally connected to the core 987 of a solenoid 988. An arm 989 extends from the bell crank including the arm 982 and a spring 990 is connected to this arm and to a spring anchor on a lug 991 carried by the side plate 912, this spring being effective to hold the parts in the position in which they are shown in Fig. 10.

When the solenoid 988 is energized the arm 982 is pivoted upwardly as is the plate 980 and the lug 984 thereon and this pivots the arm 977 upwardly to disengage the cam surface 976 thereon from the pin 975, whereupon the springs 973 cause the clutch teeth 969 to engage the clutch teeth 970 and thereupon the cam 966 starts to rotate with shaft 968. Shortly after the cam 966 starts to rotate, the pin 975 engages the plate 980 to disengage the lug 984 from the end of the arm 977 whereupon the spring 979 returns the arm 977 into engagement with the hub 974 so that near the end of a revolution of the cam 966 with the shaft 968 the pin 975 rides over the cam surface 976 to separate the clutch teeth 969 from the clutch teeth 970, and when the pin 975 comes to rest in engagement with the abutment 992 on the arm 977 the cam stops in its at rest position shown in Fig. 10.

The solenoid 988 is energized each time the movable knife 956 is to move into cooperating relation with the cutting edge on the stationary cutting member 955, this being effected after a predetermined number of impressions have been made on the web 901—W and a predetermined length of the web, which is to constitute a page, as hereinabove described, has been fed past the knife 956, pages severed from the web 901—W by the knife 956 passing into the receiver 993, Figs. 5 and 10.

The shaft 968, Figs. 7, 10, 12, 14, is rotated each time the printing and control devices D are advanced by the carrier bar as 252 and to this end the following arrangement is provided: A gear 994 is rotatably mounted on the shaft 968 and has clutch teeth 995 at the free end of a hub thereon, these clutch teeth being adapted for cooperation with clutch teeth 996 provided on a sleeve slidably

but non-rotatably mounted on the shaft 968. The clutch teeth 996 on this sleeve 997 are urged toward the clutch teeth 995 by springs 998 extended between the other end of this sleeve 997 and a collar 999 fast on the shaft 968, and it will be recognized that this arrangement is part of a clutch structure such as that disclosed in my aforesaid co-pending application, Serial No. 239,561, filed November 8, 1938, now Patent No. 2,265,133, patented December 9, 1941. A pin 1000 is fast in the sleeve 997 and is engageable with a cam surface on a plate 1001 that is pivotally mounted as indicated at 1002 on the outer face of the side plate 913, this plate being urged into engagement with the periphery of the sleeve 997 by a spring 1003. In the manner above described an arm 1004 is connected to the core 1005 of the solenoid 1006 is effective to retract the arm 1001 from engagement with the pin 1000 whereupon the springs 998 engage the clutch teeth 996 with the clutch teeth 995 to thereby connect the gear 994 to the shaft 968 and thereupon the shaft 968 is caused to make a complete revolution, the pin 1000 engaging a cam surface on the plate 1001 to disengage the clutch teeth 996 from the clutch teeth 995 at the end of this single revolution. Rotary movement is imparted to the gear 994 from the pinion 1007 mounted on a stub shaft 1008 carried by the side plate 913. A pulley 1009 is unitary with the pinion 1007 and a belt 1010 is passed about the pulley 1009 and about a pulley 1011 fast on the shaft of the motor 1012 carried by a bracket 1013 that is supported from the side plates 912 and 913. When the machine and pager and proofer are in operation the motor 1012 is constantly rotating. It is to be understood that if desired the motor 1012 and the pulley 1011 on the shaft thereof could be supplanted by a suitable pulley on the main drive shaft 19 of the machine. The use of a motor as 1012 is preferred where the pager and proofer, as in the present instance, is an attachment rather than a unitary fixed part of the machine.

It will be understood that the above referred to step by step advancing of the web 901-W is to be imparted to the web each time the shaft 968 is caused to rotate and to this end a ratchet 1014 is fast on the shaft 938 and the teeth in this ratchet are spaced apart in the amount that the web 901-W is to be advanced intermediate each impression operation thereon, a ratchet with differently and properly spaced teeth being substituted for the ratchet 1014 when a different spacing between impressions on the web is desired. A pawl 1015 pivotally mounted on a rocker 1016 is urged toward the teeth of the ratchet as 1014 by a spring 1017, the rocker 1016 being pivotally mounted on the shaft 938. One end of a link 1018 is connected to the rocker 1016 and the other end of this link is adjustably connected, as indicated at 1019, to a crank arm 1020 fast on the shaft 968. Each time the shaft 968 rotates a reciprocatory movement is imparted through the link 1018 and in the first part of this reciprocatory movement the pawl 1015, which at this time will be positioned to engage a tooth in the ratchet 1014, causes the ratchet and therefore the shaft 938 and the roller 941 thereon to make an advancing movement. In the other portion of this reciprocatory movement, which is in the opposite direction, the pawl 1016 is retracted from engagement with a given tooth on the ratchet 1014 back into position to engage the succeeding tooth, the parts coming to rest at

the time the pawl 1016 attains position to engage this succeeding tooth. The rotation imparted to the shaft 938 is sufficient to advance the web in the amount desired intermediate impressions made thereon, these impressions being made in the manner described in full detail in the manner described in my aforesaid co-pending application Serial No. 221,841.

As has been stated heretofore, a number of impressions are made on the web 901-W and this web is then divided into pages of predetermined size, and this means that the solenoid 988 is to be energized only at infrequent intervals, that is, only after a predetermined length of web has been fed past the knife 956, or stated otherwise, only after a predetermined number of impressions have been made on the web. Hence, to effect this and in order to insure that all of the pages will be of uniform size, a timing arrangement is provided which causes the solenoid 988 to be energized at times which will cause the knife 956 to be operated to sever the web 901-W after a predetermined length of web and therefore a predetermined number of impressions thereon have been fed past this knife, and this is accomplished in the following manner:

A stub shaft 1021, Figs. 7 and 8, is mounted on the outer face of the side plate 912 and a ratchet 1022 is rotatably mounted on this stub shaft, a friction spring 1023 being effective on the ratchet to prevent undesired movement thereof. A rocker 1024 is also mounted on the stub shaft 1021 and one end thereof projects into a position below the shaft 968 so as to be engageable by a pin 1025, Fig. 7, on the crank arm 1020 in each rotation of this crank arm. A pawl 1026, Fig. 8, is mounted on the other end of the rocker 1024 and is urged into engagement with the teeth of the ratchet 1022 by a spring 1027. A spring 1028 acts on the rocker 1024 and urges this rocker toward engagement with the hub of the crank arm 1020 so that this hub acts as a stop to overcome the effect of the spring 1028, the pin 1025 of course, when effective on the rocker 1024, disengaging it from the hub of the crank arm 1020.

Each time the pin 1025 engages the rocker 1024 the pawl 1026 is engaged with one tooth on the ratchet 1022 in the first part of the reciprocatory movement of the rocker 1024, to advance the ratchet 1022, and then in the latter part of this reciprocatory movement, which is, of course, in the opposite direction, the pawl 1026 is retracted slightly more than the length of one tooth on the ratchet 1022 against the action of the friction spring 1023.

A switch, generally indicated by 1029, Figs. 7 and 22, is mounted on the side plate 912 and includes blades 1030 and 1031. A sheet 1032 of insulating material is mounted on the top side 60 of the blade 1031 in position to be engaged by a pin 1033 extending from the outer face of the ratchet 1022. In the course of the advancing movement of the ratchet 1022 in a step by step manner induced as above described, the pin 1033 moves into engagement with the sheet 1032 of insulating material and thereupon a contact on the blade 1031 is engaged with a contact on the blade 1030 whereupon the switch 1029 is closed. 65 Closure of the switch 1029 conditions circuit to the solenoid 988. This circuit also includes a timing switch 1736, Fig. 22, which in the present machine is embodied in the auxiliary printing mechanism that prints the data A', N' and V' upon the web 901-W. The web feed solenoid 70

1006 and the knife control solenoid 988 are connected in parallel to be operated concurrently upon closure of switch 1736 by a cam 1795, whenever the switch 1029 is closed. During intervals when the switch 1029 is not closed, the cam 1795 and associated switch 1736 are effective to control only the solenoid 1006.

When switch 1029 is closed by the ratchet 1022 during a predetermined cycle of operation of the pager and proofer unit, it remains closed until the next movement of the ratchet 1022 in the succeeding cycle of operation of the pager and proofer. During the interval when the switch 1029 is closed, the cam 1795 closes the switch 1736 and circuit is completed from ground through conductor 1739 to terminal 1732 and thence through a conductor 1740, winding of solenoid 988, conductor 1741, and closed switch 1029 to battery, and the knife control solenoid 988 is thus energized. Concurrently therewith, ground is extended from terminal 1732 through conductor 1733 to the winding of solenoid 1006, which solenoid thereupon energizes to effect movement of the web 901-W. During the first half of the feeding cycle which is initiated upon energization of the solenoid 1006, the knife 956 remains inoperative due to the configuration of the cam 966, but during the second half of this cycle, at which time the web 901-W has completed its feeding movement and is at rest, the knife 956 is operated by the cam 966 to sever a sheet 901 which is deposited in the page receiver 993. It will be recognized that the ratchet 1022 is supplanted by another when the number of impressions caused to appear on each page is to be different from the number appearing on such page when the illustrated ratchet 1022 is used to cause severing of the web 901-W.

As has been stated, the pager and proofer is a unit excepting, of course, the stand 902. When a pager and proofer is to be used, a stand as 902 is rested on the same support as the machine and such stand is connected to an upright as 258 of the frame by an adjustable tie bar as 1034 to insure proper alignment of the axle of the paper roll as 901-R to be mounted therein. The unit including the side plates 912 and 913 is then mounted in position and this is effected in the manner now to be described.

Posts as 1035, Fig. 5, extend upwardly from and are secured to the upright 258 of the frame and a cross bar 1036 is extended between the posts as 1035 at the upper ends thereof. The bed plate 108 extends across the top edge of the cross bar 1036 and the rear portions of the lower edges of the side plates 912 and 913 are disposed on the top surface of the bed plate 108 with the rear ends of the side plates in vertical alignment with the cross bar 1036. Brackets as 1037, Figs. 5 and 8, are secured to the upper portions of the rear ends of the side plates 912 and 913, as indicated at 1038, and these brackets include arms which extend past the side members of the platen structure in outwardly spaced relation with these side members, the rear ends of these arms being pivotally connected, as indicated at 1039, to the outer faces of the side plate 254. Hence, the unit comprising the side plates 912 and 913 is pivotally mounted in position and may be pivoted about the pivotal connections 1039 to facilitate servicing or the like.

As is described more fully in my co-pending application, Serial No. 221,841, the variable data V' on each proof sheet 901, Fig. 4, are printed by an auxiliary printing mechanism which is set

up under the control of perforated record cards that are prepared as an incident to the printing of corresponding variable data upon a sheet such as S, Fig. 2. The auxiliary printing mechanism includes an accumulator which functions to receive and accumulate entries of the variable data V' that are printed upon the proof sheets 901. In the present embodiment of the invention, provision has been made for periodically printing upon the web 901-W, Fig. 10, a subtotal which is the accumulated result of all the entries of variable data V' which are printed upon a single one of the proof sheets 901, so that as each proof sheet is severed from the web 901-W it will bear not only the printed impressions of the variable data V' but also the total of such numerical items as have been printed upon the sheet.

For the purpose of operating the accumulator to control the printing of a total by the auxiliary printing mechanism, control means in the form of a cam 1800 having two lobes thereon is provided as shown in Fig. 8, and this cam 1800 is attached to the ratchet 1022. The lobes of the cam 1800 are in such angular relation to the ratchet 1022 that each lobe contacts an insulating block 1801 on a multi-contact switch generally designated 1802 prior to the time when the last numerical item V' is to be printed by the platen P on a portion of the web 901-W which is to be later severed as a proof sheet. Engagement of a lobe on the cam 1800 with the cam surface on the insulating block 1801 closes the switches 1803 and 1804 included in the switch generally designated 1802, and this is effective, in a manner explained hereinafter, to temporarily suspend the normal operation of the machine while a special total taking operation is brought about.

Referring to the wiring diagram, Fig. 22, a starting relay 1754 is provided for governing the automatic operation of the machine, as is described more fully in my aforesaid co-pending application, Serial No. 221,841, where the same reference character is applied to the corresponding starting relay. When the machine is to be initially set into automatic operation, the central push button 1743 of a switch SS is depressed to close a switch 1745 and thereupon battery is extended through a normally closed stop switch 1748 and through the switch 1745 and conductor 1751 to a terminal 1752, and from thence through a conductor 1753 to one terminal of the winding of the relay 1754, the other terminal of this winding being grounded. The relay 1754 thereupon energizes and closes a contact 1760. Such closure of the contact 1760 establishes a holding circuit for the relay 1754, which circuit extends from battery through the normally closed switch 1748, conductor 1805, normally closed contact 1757 of a relay 1758, and conductor 1806 to the contact 1760 of the relay 1754 and thence through the conductor 1753 to the winding of relay 1754. The holding circuit thus established maintains relay 1754 energized so long as both the switch 1748 and the relay contact 1757 are closed. The relay 1754, when energized, causes the machine to operate automatically through the intermediary of means not fully shown in the present disclosure but which are completely described in my aforesaid co-pending application, Serial No. 221,841.

As an incident to such automatic operation of the machine, a cam 1085 mounted on a timing cam shaft 1078, which is included in the form

printing unit of the machine, periodically closes a switch 1716 to thereupon momentarily extend battery at regular intervals through a conductor 1807 to a terminal 1808 and thence through a conductor 1809 to the winding of a clutch solenoid 717. It is the solenoid 717 which controls the operation of the auxiliary printing mechanism by operatively connecting the cam shaft thereof to the main drive shaft 19, Fig. 5, of the printing machine when said solenoid is so energized. As has been explained, the timing cam 1795, Fig. 22, included in the auxiliary printing mechanism controls the energization of the solenoid 1006, Fig. 7, which operates the means for advancing the web 901—W after each impression 15 has been made thereupon by the platen P.

By referring to Fig. 22, it will be seen that each time the cam surface on the block 1801 is engaged by a lobe on the cam 1800, the switches 1803 and 1804 are closed. Cam 1800 does not remain in position to close both the switches 1803 and 1804, however, but continues to advance into a position to engage the shoulder 1801a on the block 1801 before coming to rest. Thus, switch 1804 is only momentarily closed by the cam 1801, but switch 1803 remains closed so long as the shoulder 1801a is engaged by the cam 1800. Such momentary closure of the switch 1804 extends ground through a conductor 1810 to the winding of the relay 1758, which relay is thereupon momentarily energized to open its contact 1757 and thereby break the holding circuit to the starting relay 1754, so that the latter relay is thus de-energized. This causes the timing cam shaft 1078 to cease rotating at the end of the machine cycle in which the relay 1758 is energized, and the machine then temporarily ceases its automatic operation under control of said timing shaft, while a total-taking operation ensues, as will be described presently.

Prior to the time automatic operation of the machine is interrupted as above described, the timing cam 1085 momentarily closes the switch 1716 to energize the solenoid 717, as aforesaid, and thereupon the auxiliary printing mechanism is operated to print the last item of variable data V' on that part of the web 901—W which is later to be severed as a proof sheet. Such closure of switch 1716 also extends battery through a conductor 1811 and the closed switch 1803 to a conductor 1812 which leads to the winding of a solenoid 1813, Figs. 17, 18 and 22, which solenoid thereupon energizes and retracts its plunger, 1814. A dog 1815 is pivotally connected to the plunger 1814 and this dog is normally yieldably maintained in engagement with the periphery of a cam 1817 by a spring 1816, Fig. 19, but upon energization of the solenoid 1813 and consequent retraction of the plunger 1814, the dog 1815 is temporarily withdrawn from engagement with the cam 1817 that is fast on cam shaft 1819. Shaft 1819 tends to be constantly driven through the medium of a friction clutch 1820, Fig. 18, by a pulley 1821 that is connected through a belt to the main drive shaft 19, Fig. 5. Normally, the friction clutch 1821 merely slips, but when the dog 1815 is no longer in position to engage a notch 1818 in the cam 1817, the shaft 1819 is free to be driven by the belt pulley 1821 through the medium of the clutch 1820.

In the course of such rotation of the cam shaft 1819, a cam 1822 thereon closes a switch 1823 and battery is thereupon extended from a conductor 1824 through the switch 1823 and conductor 1825 to the winding of a solenoid 1826, Figs.

5, 21 and 22, which solenoid thereupon energizes and retracts its plunger 1827. The plunger 1827 has a pivoted connection with an arm 1828 which is connected to a lever generally designated as 862, which lever, in a manner more fully explained in my co-pending application, Serial No. 221,841, controls the total-taking operation of the auxiliary printing mechanisms. Thus, energization of the solenoid 1826 rocks the lever 862 counter-clockwise as viewed in Fig. 21 about its pivot 745 for effecting a total-taking operation, and as incident to such movement of lever 862, a stud 872 thereon engages and closes switch 873. Such closure of switch 873 closes a circuit through a conductor 1829 to the terminal 1808 and thence through conductor 1809 to the winding of the clutch solenoid 717. Thereupon the auxiliary printing mechanism is caused to go through a cycle of operation independently of the other units in the printing machine, and in the course of such operation a total is read out from the accumulator and is printed upon the web 901—W.

It is undesirable that any changeable data A' or number N', Fig. 4, shall appear opposite the printed total on the sheet 901, and hence means have been provided for suppressing the printing of such data when a total-taking operation is in progress. To this end, the platen P is constructed with two separate impression surfaces as shown in the front view of Fig. 11. The impression member 1830 which affords one of these surfaces is rigidly fastened to the plate 586 of the platen P and a rubber block 1831 secured to the under side of the member 1830 cooperates with the means that prints the variable data V' upon the web 901—W. Another impression member 1832 is mounted on the platen P and this member carries a rubber block 1833 which cooperates with the printing devices D and the printing wheels of the numbering mechanism (not shown) for printing the number N' upon the web 901—W. As is shown in Fig. 11, the plate 586 of the platen P is provided on its upper side with openings or sockets as 1834 in which screws 1835 are slidably fitted, these screws being yieldably retained in the positions shown in Fig. 11, by springs 1836 interposed between the heads of the screws 1835 and the bottoms of the sockets 1834. The shanks of the screws 1835 pass freely through suitable openings in the plate 586 at the bottoms of the sockets 1834 and the lower ends of these screws are threaded into a plate 1837 secured to the impression member 1832 of the platen P. The member 1832 is normally maintained in its lowermost position for cooperation with the printing devices D and the numbering mechanism by cams 1838 mounted for rocking movement in suitable openings in the plate 586, these cams being normally so positioned that the circular portions of their peripheries engage the upper side of the plate 1837 secured to the yieldably mounted member 1832.

Each cam 1838 is provided with a flat 1839, and when a total-taking operation is to be effected, the cams 1838 are rotated by a means to be disclosed presently, so that the flats 1839 thereon are positioned to cooperate with the member 1832. This enables the springs 1836 acting upon the screws 1835 to retract the member 1832 upwardly so that the rubber block 1833 thereon does not engage the printing device D which is in printing position at that time, nor the numbering mechanism, and hence the printing of the changeable data A' and number N', Fig. 4, is sup-

pressed. The numbering mechanism is not operated to advance its units printing wheel in this total-taking operation. Hence the only impression made upon the web 901—W will be a total of the items of variable data V' which have been printed upon that portion of the web 901—W which is to be severed as a proof sheet 901.

As shown in Figs. 7, 8 and 10, the cams 1838 extend rearwardly of the platen P and are provided at their outer ends with bevel gears 1840 which are meshed with bevel gears 1841 that are fast on a shaft 1842. The shaft 1842 is journaled in brackets 1843 carried by the platen P and this shaft is provided with a rock arm 1844 which is normally maintained in a position relative to the platen P as shown in Fig. 8, by reason of the friction between the cams 1838 and the plate 1837 in Fig. 11. A solenoid 1846 is secured to the frame of the printing machine by a bracket 1847 and a plunger 1848 of this solenoid is so positioned with respect to the arm 1844 that when the solenoid 1846 is energized, the plunger 1848 is moved into a position to engage an extension 1849 on the end of the arm 1844, when the platen P descends for printing the total on the web 901—W.

Referring again to the wiring diagram, Fig. 22, it will be observed that the cam shaft 1819 controlled by the solenoid 1813 carries a cam 1850 and when the cam shaft 1819 has rotated a predetermined distance during a total-taking cycle, the cam 1850 closes a switch 1851 to thereby close a circuit from the conductor 1824 through a conductor 1852 to the winding of the solenoid 1846 so that this solenoid is thereupon energized to eject its plunger 1848. Thus, as the platen P, Fig. 8, descends to print the total, the rock arm 1844 strikes the plunger 1848 and is rocked a limited distance clockwise as viewed in Fig. 8, and in so doing rotates the shaft 1842 carried by the platen P and thereby rocks the cams 1838, Fig. 11, to bring the flats 1839 thereon parallel with the upper surface of the member 1832. The member 1832 is, therefore, retracted upwardly by the springs 1836, and is prevented from making an impression upon the web 901—W from the printing device D and the numbering mechanism.

A bracket 1853 is mounted on the frame of the printing machine, as shown in Fig. 7 and fragmentarily represented in Fig. 8, and the upper end of this bracket overlies the extension 1849 of the rock arm 1844 near the upper limit of the path of movement thereof. When a total printing operation has been effected and the platen P is returned to its normal upper position, the extension 1849 engages the upper end of the bracket 1853 and is rocked counterclockwise, as shown in Fig. 8, sufficiently to restore the cams 1838, Fig. 11, so that the circular portions of these cams again bear against the upper surface of the member 1832, thereby bringing this member into its lowermost position with relation to the platen P against the action of the springs 1836.

In the course of the total printing operation the web feed solenoid 1006 is energized, in the manner explained hereinabove, to effect feeding of the web 901—W and advance of the ratchet 1022, Figs. 8 and 22, after the total has been printed upon the web. The lobe on the cam 1800 thereupon moves from engagement with the shoulder 180a on the block 1801, enabling the switch 1803 to open. Such opening of the switch 1803 is without effect, however, inasmuch as solenoid 1813 was previously deenergized upon open-

ing of the switch 1716 controlled by the timing cam 1085.

Toward the end of the total-taking cycle, cam 1854 on the cam shaft 1819 momentarily closes a switch 1855 to thereby close a circuit from the conductor 1824 through a conductor 1856 to a terminal 1852 and thence through a conductor 1753 to the winding of the relay 1754 which thereupon energizes and closes its contact 1760. The closure of the contact 1760 establishes a holding circuit for the relay 1754, inasmuch as the relay 1758 is in a deenergized state, having been only momentarily energized prior to the total taking cycle as explained hereinabove. The solenoid 1813 was likewise only momentarily energized by the timing switch 1716 to withdraw the dog 1815 from the cam 1817, so that the dog 1815 shortly thereafter returns into engagement with the periphery of the cam 1817, and when this cam has completed a full revolution, the dog 1815 seats in the notch 1818 in the periphery thereof and thereby arrests the shaft 1819 at the end of a revolution. Cams 1822, 1850 and 1854 are disengaged from their switches 1823, 1851 and 1855, respectively, toward the close of the total-taking cycle so that the solenoids 1826 and 1846 are released and the energizing circuit from the switch 1855 to the relay 1754 is broken. However, relay 1754 remains locked up through its holding circuit as aforesaid and automatic operation of the printing machine is therefore resumed under control of the timing cam shaft after the total has been printed.

If it is necessary to stop the machine at any time in the course of operation thereof, the holding circuit to the relay 1754 may be broken by depressing the shell 1767 of the switch SS to thereby open the switch 1748. Relay 1754 thereafter deenergizes, and a predetermined time thereafter the automatic operation of the machine is interrupted. However, if a total is to be printed at this time, the timing switch 1716 is closed by the cam 1085 before the timing cam 1078 ceases rotating to thereby energize the solenoid 1813 for enabling the auxiliary printing mechanism to go through an extra cycle of operation in which the total is printed upon the proof web.

It will be manifest from the foregoing description that I have provided a pager and proofer that is in the form of a unit which may be readily attached to or detached from a printing machine. Furthermore, by reason of the fact that this unit includes electrically controlled clutches, it is only necessary that suitable switch means be incorporated in operative units of the machine in order to bring about the desired operation of the pager and proofer. As explained hereinabove, such controlling may be advantageously incorporated in the particular units in the machine with respect to which operation of the pager and proofer is to be timed, and in this way operation of the pager and proofer in properly timed relation with cooperating parts of the machine may be assured.

It will be particularly noted that the means for dividing the web on which the impressions are made into pages is included in and is operated under control of the means for advancing the web. This arrangement insures accurate operation of the severing means for operation of the severing means, by such an arrangement, is fully correlated with the operation of the web advancing means. Furthermore, this arrangement is such that while operation of the severing means

is under control of the means for advancing the web, such means operate to condition the severing means for operation and operation of the severing means is brought about by the means which effect operation of the web advancing means. This arrangement is obviously advantageous for it insures that the severing means will be operated at a time when the web is at rest in the course of the step-by-step advancing movement imparted thereto by the web advancing means.

Moreover, it will be manifest from the description hereinabove that I have provided a simple and efficient means for printing what are commonly called sub-totals at the bottom of the various pages into which the web is to be divided. The arrangement is such that such totals will be printed prior to the time the web is divided into pages and it will be apparent that the means that I have provided herein enable the web to be divided in such a way that the sub-totals will appear on the page to which they are related.

Many other advantages of the present invention will be apparent to those skilled in the art from the foregoing description and it is to be understood that while I have illustrated and described a selected embodiment of my invention this is capable of variation and modification and I, therefore, do not wish to be limited to the precise details set forth but desire to avail myself of such changes and alterations as fall within the purview of the following claims.

I claim:

1. In a proofer and pager for use with a printing machine having impression means defining a printing station, means for feeding a web past the printing station in the machine, driving means for said web advancing means, clutch means operatively interposed between said driving means and said web advancing means and effective when operated to enable said driving means to actuate said web feeding means for advancing a predetermined amount of web past said printing station, timing means controlled by said printing machine for intermittently operating said clutch means, severing means effective when operated to cut a proof sheet from the printed portion of said web, other clutch means for operatively connecting said severing means to said driving means when a severing operation is to be performed, and other timing means operable by said web advancing means and operating when a predetermined number of web advancing operations have been effected to condition said other clutch means to be operated by the first-named timing means.

2. In a proofer and pager for intermittently feeding a proof web past printing means to have items of data successively printed thereupon and in which the web is divided into proof sheets after being thus printed, the combination, with driving means, of a web feeding means including a driven shaft, intermittently operated clutch means effective during each operation thereof to clutch said driven shaft to said driving means for a predetermined period during a certain portion of which said web feeding means is driven to advance the web in a predetermined amount, web severing means including a knife and operating means therefor, other clutch means effective when operated to clutch said knife operating means to said driven shaft for operating said knife to cut a proof sheet from said web during a time when the web is stationary, and means responsive to advancing movement of the web

5 feeding means and operating at predetermined intervals to condition said other clutch means for operatively connecting said knife operating means to said driven shaft during the next succeeding operation thereof.

3. In a proofer and pager for intermittently feeding a proof web past printing means to have items of data successively printed thereupon and in which the web is divided into proof sheets 10 after being thus printed, the combination, with driving means, of a web feeding means including a driven shaft, clutch means effective during each operation thereof to clutch said driven shaft to said driving means for a predetermined period during a certain portion of which said web feeding means is driven to advance the web in a predetermined amount, timing means for intermittently operating said clutch means, web severing means including a knife and operating 15 means therefor, other clutch means effective when operated to clutch said knife operating means to said driven shaft for operating said knife to cut a proof sheet from said web during a time when the web is stationary, and means 20 responsive to advancing movement of the web feeding means and operating at predetermined intervals to condition said other clutch means for operatively connecting said knife operating means to said driven shaft under control of said 25 timing means.

4. In a proofer and pager for intermittently feeding a proof web past printing means in a printing machine to have successive impressions made thereon, an intermittently actuated drive shaft, web feeding means, means operatively connecting said web feeding means to said drive shaft to be driven thereby during only a portion of a revolution each time when said shaft is actuated, a knife for severing the printed portion of the web into proof sheets, knife operating means, coupling means for operatively connecting said knife operating means to said drive shaft, and control means so constructed and arranged as to be effective when a predetermined number of 40 actuations of said drive shaft have been effected to condition said coupling means for connecting said knife operating means to said drive shaft during a predetermined actuation thereof, said knife operating means being constituted and arranged to operate said knife to sever a sheet at 45 a time during the actuation of said drive shaft when the web is at rest.

5. In a proofing and paging attachment for a printing machine wherein a succession of printing operations are adapted to be performed, intermittently operable web feeding means for feeding a web in a limited amount during each operation thereof, timing means for synchronizing the operation of said web feeding means with that of the printing machine, severing means effective in each operation thereof to cut a sheet from the printed portion of the web, and other timing means operated by said web feeding means when a predetermined number of web feeding operations have been effected thereby for placing said severing means under the direct control of the first-named timing means.

6. In a proofer and pager for use with a printing machine wherein a succession of printing operations are adapted to be performed, a driving shaft, rotary means for feeding a web past a printing station in the machine, a one-revolution clutch interposed between said driving shaft and said web feeding means and effective when 70 operated to enable said driving shaft to actuate

said web feeding means for advancing a predetermined amount of web past said printing station, timing means included in the printing machine for intermittently operating said one-revolution clutch, severing means effective when operated to cut a proof sheet from the printed portion of said web, another one-revolution clutch for operatively connecting said severing means to said driving shaft when a severing operation is to be performed, and means controlled by said web feeding means and effective when a predetermined number of web advancing operations have been effected to condition said other one-revolution clutch for operation under control of the timing means.

7. In a proofer and pager for use with a list printing machine wherein a succession of printing operations are adapted to be performed, an intermittently rotated drive shaft, rotary web feeding means, means connecting said web feeding means to said drive shaft to be actuated thereby during a portion of each cycle of rotation thereof, a web cutting knife, knife operating means including a rotatable member effective when actuated to operate said knife during a portion of a cycle of rotation thereof, means including a rotatable timing member and effective when said timing member is in predetermined angular relation to condition said knife operating means for subsequently enabling the first-named rotatable member to be driven by said drive shaft to thereby operate said knife, said rotatable member operating said knife during a time in the cycle of rotation of said drive shaft when said web feeding means is inactive, and means connecting said timing member to said drive shaft for stepwise rotative movement in synchronism with the intermittent rotation of said shaft.

8. In a proofer and pager for intermittently feeding a proof web past printing means to have items of data successively printed thereupon and in which the web is divided into proof sheets after being thus printed, the combination, with rotary driving means, of a web feeding means including a driven shaft, clutch means effective during each operation thereof to clutch said driven shaft to said driving means for a cycle of rotation during a certain portion of which said web feeding means is driven to advance the web in a predetermined amount, timing means for intermittently operating said clutch means, web severing means including a knife and rotary operating means therefor effective during a portion of a cycle of rotation thereof to operate said knife, other clutch means operable to clutch said knife operating means to said driven shaft, means including a rotatable timing member effective when in predetermined rotative position to condition said other clutch means for operatively connecting said knife operating means to said driven shaft during a predetermined cycle of rotation thereof, said knife being operated at a time in the rotation of said driven shaft when said web feeding means is inactive, and means for imparting stepwise rotative movement to said timing member in synchronism with the intermittent actuation of said driven shaft to thereby condition said other clutch means for operation only when a predetermined number of web feeding operations have been effected.

9. In a proofer and pager for use with a printing machine wherein a succession of printing operations are adapted to be performed, a driving shaft, rotary means for feeding a web past a

printing station in the machine, an intermittently operated one-revolution clutch interposed between said driving shaft and said web feeding means and effective in each operation thereof to enable said driving shaft to actuate said web feeding means for advancing a predetermined amount of web past said printing station, severing means effective when operated to cut a proof sheet from the printed portion of said web, another one-revolution clutch for operatively connecting said severing means to said driving shaft when a severing operation is to be performed, means controlled by said web feeding means and effective when a predetermined number of web advancing operations have been effected to condition said other one-revolution clutch for operation, and timing means for operating said other one-revolution clutch when it has been thus conditioned.

10. In a proofer and pager for intermittently feeding a proof web past printing means in a printing machine to have successive impressions made thereon, an intermittently actuated drive shaft, web feeding means, means operatively connecting said web feeding means to said drive shaft to be driven thereby during only a portion of each time when said shaft is actuated, a knife for severing the printed portion of the web into proof sheets, knife operating means, coupling means for operatively connecting said knife operating means to said drive shaft, control means so constructed and arranged as to be effective when a predetermined number of actuations of said drive shaft have been effected to condition said coupling means for connecting said knife operating means to said drive shaft, and timing means for operating said coupling means when it has been thus conditioned, said knife being operated by said knife operating means to sever a sheet at a time during the actuation of said drive shaft when the web is at rest.

11. In a proofer and pager for use with a list printing machine wherein a succession of printing operations are adapted to be performed, an intermittently rotated drive shaft, rotary web feeding means, means connecting said web feeding means to said drive shaft to be actuated thereby during a portion of each cycle of rotation thereof, a web cutting knife, knife operating means including a rotatable member effective when actuated to operate said knife during a portion of a cycle of rotation thereof, means including a rotatable timing member and effective when said timing member is in predetermined angular relation to condition said knife operating means, other timing means for subsequently actuating the thus conditioned knife operating means to thereby enable the first-named rotatable member to be driven by said drive shaft for operating said knife, said rotatable member operating said knife during a time in the cycle of rotation of said drive shaft when said web feeding means is inactive, and means connecting said timing member to said drive shaft for stepwise rotative movement in response to the intermittent rotation of said shaft.

12. In a proofer and pager for use with a list printing machine wherein a succession of printing operations are adapted to be performed, an intermittently rotated drive shaft having a crank at one end thereof, rotary web feeding means, a pawl and ratchet mechanism connecting said web feeding means to said crank to be actuated thereby during a portion of each cycle of rotation of said drive shaft, a web cutting knife, a cam ef-

fective when rotated to operate said knife during a portion of the cycle of rotation thereof, a clutch for connecting said cam to said drive shaft, a solenoid for operating said clutch, a rotatable switch member effective when in predetermined angular position to condition said knife operating clutch solenoid, a timing switch for subsequently energizing the thus conditioned solenoid to thereby operate said clutch for operatively connecting said cam to said drive shaft at the initiation of a predetermined cycle of rotation of said shaft, said cam operating said knife during a time in such cycle of rotation of said drive shaft when said web feeding means is inactive, and a pawl and ratchet mechanism connecting said rotatable switch member to said crank for stepwise rotative movement in synchronism with the intermittent rotation of said drive shaft.

13. In a printing machine in which impressions are made from successively fed printing devices onto an intermittently fed proof web or the like in conjunction with the printing of numerical data from variable printing means onto said web, a reciprocatory platen for making such impressions and printing such numerical data onto the web and including a fixed impression member for cooperation with the variable printing means and a relatively movable impression member which is adjustable to an operative position for cooperation with a printing device when said platen is moved into printing position and adjustable to an inoperative position with respect to such a printing device when an impression is not to be effected therefrom, control means normally maintaining said movable impression member in its operative position but operable when an impression is not to be made from a printing device to adjust said movable impression member to its inoperative position, and means responsive to advancing movement of the proof web and effective when a predetermined amount of the web has been fed past the printing means to operate said control means for adjusting said movable impression member to its inoperative position whereby no impression is made from the printing device then in printing position.

14. In a printing machine in which impressions are made from successively fed printing devices onto an intermittently fed proof web or the like in conjunction with the printing of numerical data from variable printing means onto said web, a reciprocatory platen for making such impressions and printing such numerical data onto the web and including a fixed impression member for cooperation with the variable printing means and a relatively movable impression member which is adjustable to an operative position for cooperation with a printing device when said platen is moved into printing position and adjustable to an inoperative position with respect to such a printing device when an impression is not to be effected therefrom, control means normally maintaining said movable impression member in its operative position but operable when an impression is not to be made from a printing device to adjust said movable impression member to its inoperative position, means effective when actuated to operate said control means for adjusting said movable impression member to its inoperative position during that part of the reciprocating movement of said platen when an impression is normally effected, and means operating in dependence upon advancing movement of the web for periodically conditioning the last-named means to be oper-

ated during a predetermined reciprocation of the platen.

15. In a printing machine in which impressions are made from successively fed printing devices onto a proof web or the like in conjunction with the printing of numerical data from variable printing means onto said web, a reciprocatory platen for making such impressions and printing such numerical data onto the web and including a fixed impression member for cooperation with the variable printing means and a relatively movable impression member which is adjustable to an operative position for cooperation with a printing device when said platen is moved into printing position and adjustable to an inoperative position with respect to such a printing device when an impression is not to be effected therefrom, means for feeding the web in a limited amount following each reciprocation

20 of said platen to and from printing position, control means normally maintaining said movable impression member in its operative position but operable when an impression is not to be made from a printing device to adjust said movable impression member to its inoperative position, means controlled by said web feeding means for periodically conditioning said control means for operation, and timing means for operating said control means when so conditioned.

30 16. In a printing machine in which impressions are made from successively fed printing devices onto a proof web or the like, a reciprocatory platen for making such impressions and including a relatively movable impression member which is adjustable to an operative position for cooperation with a printing device when said platen is moved into printing position and adjustable to an inoperative position with respect to such a printing device when an impression is not to be effected therefrom, means for feeding the web in a limited amount following each reciprocation of said platen to and from printing position, control means normally maintaining said movable impression member in its operative position but operable when an impression is not to be made from a printing device to adjust said movable impression member to its inoperative position, and means controlled by said web feeding means for periodically operating said control means to suppress the making of an impression on the web by said platen.

50 17. In a printing machine in which impressions are made from successively fed printing devices onto a proof web or the like, a reciprocatory platen for making such impressions and including an impression member yieldably mounted thereon for movement relative thereto, a cam rockably mounted in said platen and normally maintaining said movable impression member in an operative position for cooperation with a printing device when said platen is moved into printing position, means for feeding the web in a limited amount following each reciprocation of said platen to and from printing position, means for rocking said cam to thereby adjust said movable impression member to its inoperative position when an impression is not to be made from a printing device, and means controlled by said web feeding means for periodically operating said rocking means to suppress the making of an impression on the web by said platen.

60 18. In a printing machine in which impressions are made from successively fed printing devices onto a proof web or the like, a reciprocatory platen for making such impressions and includ-

ing an impression member yieldably mounted thereon for movement relative thereto, a cam rockably mounted in said platen and normally maintaining said movable impression member in an operative position for cooperation with a printing device when said platen is moved into printing position, means for feeding the web in a limited amount following each reciprocation of said platen to and from printing position, means for rocking said cam to thereby adjust said movable impression member to its inoperative position when an impression is not to be made from a printing device, means controlled by said web feeding means for periodically operating said rocking means to suppress the making of an impression on the web by said platen, and means for restoring said cam after each actuation thereof by said rocking means to thereby return said movable impression member to its normal operative position.

19. In a proofer and pager for use with a printing machine wherein a succession of printing operations are adapted to be performed, means for feeding a web past a printing station in the machine, driving means for said web advancing means, clutch means operatively interposed between said driving means and said web advancing means and effective when operated to enable said driving means to actuate said web feeding means for advancing a predetermined amount of web past said printing station, timing means controlled by said printing machine for intermittently operating said clutch means, severing means effective when operated to cut a proof sheet from the printed portion of said web, means for operating said severing means from said driving means when a severing operation is to be performed, and other timing means controlled by said web advancing means and operable when a predetermined number of web advancing operations have been effected to condition the means for operating said severing means to be operated by the first-named timing means.

20. In a pager and proofer for use with a printing machine wherein a succession of printing operations are adapted to be performed, means for feeding a web past a printing station in the machine, driving means for said web advancing means, means for connecting said web advancing means to said driving means and constituted and arranged to enable said driving means to actuate said web feeding means to advance a predetermined amount of web past said printing station, timing means controlled by said printing machine for rendering the means for operating said web advancing means from said driving means operative intermittently, severing

means effective when operated to cut a proof sheet from the printed portion of said web, clutch means for operatively connecting said severing means to said driving means when a severing operation is to be performed, and other timing means controlled by said web advancing means and operable when a predetermined plurality of web advancing operations have been effected to condition said clutch means to be operated by the first-named timing means.

21. In a proofer and pager for use with a printing machine wherein a succession of printing operations are adapted to be performed, a driving shaft, rotary means for feeding a web past a printing station in the machine, a one-revolution clutch interposed between said driving shaft and said web feeding means and effective when operated to enable said driving shaft to actuate said web feeding means for advancing a predetermined amount of web past said printing station, timing means included in the printing machine for intermittently operating said one-revolution clutch, severing means effective when operated to cut a proof sheet from the printed portion of said web, means for operatively connecting said severing means to said driving shaft when a severing operation is to be performed, and means controlled by said web feeding means and effective when a predetermined plurality of web advancing operations have been effected to condition the means for operating said severing means from said driving shaft for operation under control of the timing means.

22. In a pager and proofer for use with a printing machine, a driving shaft, rotary means for feeding a web past a printing station in the machine, means for operatively connecting said web feeding means to said driving shaft and constituted and arranged to enable said driving shaft to actuate said web feeding means to advance a predetermined amount of web past said printing station, timing means included in the printing machine for rendering the means for connecting said web feeding means to said driving shaft operative intermittently, severing means effective when operated to cut a proof sheet from the printed portion of said web, a one-revolution clutch for operatively connecting said severing means to said driving shaft when a severing operation is to be performed, and means controlled by said web feeding means and effective when a predetermined plurality of web advancing operations have been effected to condition said one-revolution clutch for operation under control of the timing means.

WALTER T. GOLLWITZER.
